UNITED STATES PATENT OFFICE.

JAMES L. HAMILTON, OF GRAND JUNCTION, COLORADO, ASSIGNOR TO HAMILTON
ORCHARD HEATER COMPANY, OF WHEELING, WEST VIRGINIA, A CORPORATION
OF WEST VIRGINIA.

ORCHARD-HEATER.

1,099,175.

Specification of Letters Patent. Patented June 9, 1914.

Application filed February 24, 1914. Serial No. 820,429.

To all whom it may concern:

Be it known that I, JAMES L. HAMILTON, a citizen of the United States of America, and resident of Grand Junction, county of 5 Mesa, and State of Colorado, have invented certain new and useful Improvements in Orchard-Heaters, of which the following is a specification.

This invention relates broadly to orchard 10 heaters; and it has for its primary object to provide a heater of the oil-burning type having improved means for increasing its efficiency as a producer of heat.

A further object of the invention is to provide an orchard heater of the character mentioned having separate means supplying air to the interior of the oil container and to the lower portion of the stack for mixing with the gases arising from said container, and 20 provided with means whereby both of said air supplies are regulated by a single adjustment.

A still further object is to provide a heater in which is attained combustion of such a 25 character as will, in a large measure, if not wholly, obviate the production of soot or carbon, and, consequently, prevent the collection of the carbon deposits which so frequently clog the draft perforations of such 30 devices, detrimentally affecting their operation, if not rendering them wholly inefficient.

Another object is to provide a heater in which heated air is introduced to the stack in such manner as to produce a high order 35 of carburation of the gases.

A further object within the contemplation 40 of the invention is to provide an orchard heater wherein is employed a plurality of separate and independent stacks arranged in a cluster.

With these and other objects in view, the invention resides in the features of construction, arrangement of elements and combinations of parts which will hereinafter be 45 exemplified, reference being had to the accompanying drawings, forming a part of this specification, in which—

Figure 1 is a top plan view of the invention; Fig. 2 is a longitudinal section on the 50 line 2—2, Fig. 1; Fig. 3 is a cross section on the line 3—3, Fig. 2; Fig. 4 is a view similar to Fig. 1, illustrating a modification; Fig. 5 is a longitudinal section on the line 5—5,

Fig. 4; and Fig. 6 is a cross section on the line 6—6, Fig. 5.

Referring to said drawings, in which like designating characters distinguish like parts throughout the several views—1 indicates an oil container which may be of any suitable shape, but which is herein illustrated as rectangular. Mounted upon said container is a cover 2 of upwardly dished form, to which a flat plate or diaphragm 3 is attached, as by seating the edges of said diaphragm within the embrace of a peripheral outwardly directed crimp or fold 4 formed in said cover adjacent to its lower lateral edges. Provided on said cover 2 at a suitable point is an elevated portion 5, of frusto-conical form, as is clearly shown in Fig. 2. The upper open 55 end of said portion 5 closely embraces the body of an upright stack 6 which has its lower end seated within an opening 7 provided therefor in the underlying diaphragm 3. Provided in the cover 2 at a point laterally of the elevated portion 5 is a circular opening 8 in which is fitted the upper end of a tube 10 the body of which is projected through an opening 9 in the diaphragm, said tube being adapted to admit air to the 60 interior of the container for mixing with the gases arising from the fuel contained in the latter, and having one or more side-openings 11 provided therein below the point embraced by said diaphragm for permitting air 65 to pass to said container even though its lower end be submerged in the oil, as shown in Figs. 2, 3, 5 and 6. Said tube is preferably detachable, having an annular flange 70 12 formed at its upper end adapted to seat upon the cover 2. Provided in said cover adjacent to the upper end of the tube 10 is a circular row of perforations 13 through 75 which air may be admitted to the passage 14 formed between the body of said cover and the diaphragm. As shown, the perforations 13 register with similar perforations provided in the overlying flange 12; but, as is apparent, said flange may be made of such less width that it will not overlie the said 80 perforations 13. A damper 15 of appropriate form, pivoted on the cover 2, is adapted to be adjusted to close the mouth of the tube 10 and the said perforations 13 to any desired extent for simultaneously regulating the air 85 supply admitted to the container and to the

passage 14, the latter being in open communication with the annular chamber 16 which is constituted between the stack 6 and the elevated portion 5. Numerous small perforations 17 provided in the stack at points intermediate the diaphragm and the point embraced by the portion 5 serve to admit to said stack the air which is conducted through the passage 14, there to mix with the gases from the container for facilitating combustion.

In the modification illustrated in Figs. 4, 5 and 6, three separate stacks 6^a, preferably arranged in a cluster, are shown. The elevated portion 5^a through which said stacks are projected has a substantially platform shape with each stack separately embraced. The employment of a plurality of stacks has been found to be advantageous in that a more thorough commingling therein of the introduced air with the gases is effected than is possible in a single large stack.

Before reaching the apertures or perforations 17 in the stack, the air admitted to the passage 14 becomes heated from contact with the diaphragm 3 and cover 2. This heated air, introduced to the stack through said perforations, commingles with the gases arising from the container, resulting in a mixture which burns with a clear hot flame and without disengaging particles of carbon. As is well known, the introduction of air direct from the atmosphere into a stack near its base is attended by various objectionable results, chief among which is the deposit of carbon on the walls of the stack, said carbon being the result of condensation due to imperfect combustion of the gaseous mixture. In other words, the cold air so introduced does not unite with the gases to produce proper combustion, but tends to produce a condensation of carbon, particles of which adhere to the interior walls of the stack and to the edges of the perforations to such an extent that said perforations quickly become clogged and entirely closed, in which condition they of course fail to perform their intended function.

The introduction of heated air through the perforations, as hereinbefore indicated, obviates the freeing of the carbon, the stack remains clear and clean, and the apertures or perforations are left wholly free from carbon deposits.

55 What is claimed is—

1. An orchard heater comprising a fuel container, a cover surmounting said container, a diaphragm occupying a position between the body of said cover and said container whereby a passage is constituted between said cover and said diaphragm, said cover having apertures for admitting air to said passage, a stack having its body embraced by said cover mounted on said diaphragm and having communication through

the latter with the interior of said container, the portion of said stack disposed between said cover and said diaphragm being apertured, and means projected through said cover and said diaphragm for conducting air to said container. 70

2. An orchard heater comprising a fuel container, a cover surmounting said container, a diaphragm occupying a position between the body of said cover and said container whereby a passage is constituted between said cover and said diaphragm, said cover having apertures for admitting air to said passage, a stack having its body embraced by said cover mounted on said diaphragm and having communication through the latter with the interior of said container, the portion of said stack disposed between said cover and said diaphragm being apertured, means projected through said cover 75 and said diaphragm for conducting air to said container, and adjustable means for regulating the draft through said conducting means.

3. An orchard heater comprising a fuel 90 container, a cover surmounting said container, a diaphragm occupying a position between the body of said cover and said container whereby a passage is constituted between said cover and said diaphragm, said cover having apertures for admitting air to said passage, a stack having its body embraced by said cover mounted on said diaphragm and having communication through the latter with the interior of said container, 95 the portion of said stack disposed between said cover and said diaphragm being apertured, means projected through said cover and said diaphragm adjacent to the cover apertures for admitting air to said container, 100 and adjustable means for regulating the volume of air admitted through said cover apertures and through said conducting means. 105

4. An orchard heater comprising a fuel 110 container, a cover surmounting said container, a diaphragm occupying a position between the body of said cover and said container whereby a passage is constituted between said cover and said diaphragm, said 115 cover having apertures for admitting air to said passage, a stack having its body embraced by said cover mounted on said diaphragm and having communication through the latter with the interior of said container, 120 the portion of said stack disposed between said cover and said diaphragm being apertured, a tube projected through said cover and said diaphragm for conducting air to said container, and means for simultaneously regulating the volume of air admitted 125 through said cover apertures and through said tube.

5. An orchard heater comprising a fuel container, a cover surmounting said con- 130

5 tainer, a diaphragm occupying a position between the body of said cover and said container whereby a passage is constituted between said cover and said diaphragm, said cover having apertures for admitting air to said passage, a stack having its body embraced by said cover mounted on said diaphragm and having communication through the latter with the interior of said container, 10 the portion of said stack disposed between said cover and said diaphragm being apertured, and a draft tube depending from said cover within the container, said diaphragm being apertured to admit of the introduction 15 of said tube.

6. An orchard heater comprising a fuel container, a cover surmounting said container, a diaphragm occupying a position between the body of said cover and said container whereby a passage is constituted 20 between said cover and said diaphragm, said cover having apertures for admitting air to said passage, a stack having its body embraced by said cover mounted on said diaphragm and having communication through the latter with the interior of said container, the portion of said stack disposed between said cover and said diaphragm being apertured, a draft tube depending from said 25 cover within the container, said diaphragm being apertured to admit of the introduction of said tube, and adjustable means for regulating the drafts through said tube and through the cover apertures.

7. An orchard heater comprising a fuel container, a cover surmounting said container, a diaphragm occupying a position between the body of said cover and said container whereby a passage is constituted 30 between said cover and said diaphragm, said cover having apertures for admitting air to said passage, a stack having its body embraced by said cover mounted on said diaphragm and having communication through the latter with the interior of said container, the portion of said stack disposed between said cover and said diaphragm being apertured, a draft tube depending from said 35 cover within the container, said diaphragm being apertured to admit of the introduction of said tube, and a damper for simultaneously regulating the drafts through said tube and through the cover apertures.

8. An orchard heater comprising a fuel 40 container, a cover surmounting said container, a diaphragm occupying a position between the body of said cover and said container whereby a passage is constituted between said cover and said diaphragm, a 45 stack or stacks mounted on said diaphragm and embraced by said cover, the portion of the stack disposed between said cover and said diaphragm being apertured, a draft tube carried by said cover at a point laterally of the stack and having its lower end 50

disposed within said container, said cover having apertures therein for admitting air to said passage, and means for regulating the drafts through said tube and the cover apertures.

9. An orchard heater comprising a fuel container, a cover surmounting said container, a diaphragm occupying a position between the body of said cover and said container whereby a passage is constituted between said cover and said diaphragm, a stack or stacks mounted on said diaphragm and embraced by said cover, the portion of the stack disposed between said cover and said diaphragm being apertured, a draft 55 tube carried by said cover at a point laterally of the stack and having its lower end disposed within said container, said cover having a series of apertures disposed adjacent to said tube for admitting air to said passage, and means for simultaneously regulating the drafts through said tube and the cover apertures.

10. An orchard heater comprising a fuel container, a cover surmounting said container, a diaphragm occupying a position between the body of said cover and said container whereby a passage is constituted between said cover and said diaphragm, an elevated portion provided on said cover, a stack projected vertically through said elevated portion and having its lower end communicating through said diaphragm with the interior of said container, that portion of said stack disposed between the elevated portion of the cover and said diaphragm being perforated for admitting air from said 60 passage to the stack, means admitting air to said passage and means for introducing air to the container.

11. An orchard heater comprising a fuel container, a cover surmounting said container, a diaphragm occupying a position between the body of said cover and said container whereby a passage is constituted between said cover and said diaphragm, an elevated portion provided on said cover, a plurality of stacks projected vertically through said elevated portion and having their lower ends communicating through 65 said diaphragm with said container, the portions of the stacks located between said elevated portion and said diaphragm being perforated, means for introducing air to the container, and means admitting air to said 70 passage.

12. In an orchard heater, the combination with a fuel container and a cover therefor, of an inclosed passage formed beneath said cover, means controlling the admission of 75 air to said passage, and a stack in open communication with said container and having a portion of its body located within said passage, said portion having perforations 80 thereof.

13. In an orchard heater, the combination with a fuel container and a cover therefor, of an inclosed passage formed beneath said cover, means controlling the admission of air to said passage, and a plurality of stacks in open communication with said container and having portions of their bodies located within said passage, each of said body portions being provided with numerous small perforations.

14. In an orchard heater, the combination with a fuel container and a cover therefor, of an inclosed passage formed beneath said cover, means controlling the admission of

air to said passage, a plurality of stacks in 15 open communication with said container and having portions of their bodies located within said passage, each of said body portions being provided with numerous small perforations, and controllable means for admitting an air supply to said container. 20

In testimony whereof, I affix my signature in presence of two subscribing witnesses.
